Des. 201,009
Patented May 4, 1965

201,009

DOOR PULL

John J. Grove, Dallas, Tex., assignor to Facade, Inc.,
Richardson, Tex., a corporation of Texas

Filed June 24, 1963, Ser. No. 75,492

Term of patent 14 years

(Cl. D10—8)

FIG. 1

FIG. 3

FIG. 2

FIG. 1 is an isometric view of a door pull showing my new design;

FIG. 2 is an end view thereof; and

FIG. 3 is a side elevational view.

I claim:

The ornamental design for a door pull, as shown.
